Attorney

UNITED STATES PATENT OFFICE.

JOHN HOWARD THORNTON, OF NASHVILLE, TENNESSEE.

MITER-BOX.

1,381,033.

Specification of Letters Patent. Patented June 7, 1921.

Application filed November 1, 1919. Serial No. 334,928.

To all whom it may concern:

Be it known that I, JOHN HOWARD THORNTON, a citizen of the United States, residing at Nashville, in the county of Davidson and

5 State of Tennessee, have invented certain new and useful Improvements in Miter-Boxes, of which the following is a specification.

The invention relates to a miter box and 10 more particularly to the class of miter frames for use with hack saws for cutting pipes, bars or the like.

The primary object of the invention is the provision of a frame of this character, 15 wherein the same will receive a pipe or bar, the latter being held in place by hand or by mechanical means, so that the pipe or bar can be cut at the proper angle or cut in two sections, as the hack saw is guided in the 20 frame through a kerf or slot formed therein, thereby enabling the accurate cutting of the pipe or bar so as to shear the same square without bending in the ends and thus avoiding the reducing of the capacity of the pipe 25 when being cut.

Another object of the invention is the provision of a box or frame of this character, wherein the construction thereof is novel in form so that the same can be readily applied 30 to a pipe, bar or the like to be cut, and when thereon will enable the firm gripping of the pipe, bar or the like and the frame so as to avoid any possibility of relative displacement of either the box or frame and the 35 pipe, bar or the like.

Another object of the invention is the provision of a box or frame of this character, wherein the bar or the like can be properly and accurately cut, the box or frame 40 being readily handled by the user of the saw, thereby minimizing labor in its use, as it avoids the necessity of an attendant in cutting pipes, bars or the like.

A still further object of the invention is 45 the provision of a box or frame of this character, which is extremely simple in construction, thoroughly reliable and efficient in its purpose, strong, durable and inexpensive to manufacture.

50 With these and other objects in view, the invention consists in the features of construction, combination and arrangement of parts as will be hereinafter fully described, illustrated in the accompanying drawing and 55 pointed out in the claims hereunto appended.

In the accompanying drawing:

Figure 1 is a perspective view of the miter box or frame constructed in accordance with the invention showing the same in position 60 relative to a pipe to be cut and the hack saw engaged in the box or frame in cutting position.

Fig. 2 is an enlarged fragmentary side elevation of the pipe showing the miter box 65 or frame thereon.

Fig. 3 is an end elevation showing the miter box or frame bridging the pipe.

Similar reference characters indicate corresponding parts throughout the several 70 views in the drawings.

Referring to the drawing in detail, A designates a portion of a pipe, illustrative of a piece of work to be cut in the use of the miter box B with the hack saw C, the latter 75 being of the ordinary well known construction, while the miter box B will be hereinafter fully described.

The miter box comprises a substantially V-shaped frame or body 5, preferably made 80 from metal, although the same may be made from any other suitable material and when applied to the work to be cut is inverted as is clearly shown in Figs. 1, 2 and 3 of the drawing. The frame or body 5 includes 85 side portions 6 which are for a major portion of their length cutaway to provide finger recesses 7 for accommodating the fingers and the thumb of the hand of the user when the frame or body 5 is applied to the 90 pipe A, bar or other piece of work to be cut by the hack saw C in the manner as shown in Fig. 1 of the drawing.

The frame or body 5 on opposite sides of the recesses 7 constitute guides 8 and 9 respectively, the guide 8 being of considerably greater size than the guide 9 and in this said guide 8 transversely of the frame or body 5 is a kerf or slot 10 of a size to accommodate the blade of the saw C, as shown inserted in 100 the kerf or slot 10 of the miter box or frame in Fig. 1 of the drawing, to permit reciprocation of the blade of the saw in the operation thereof for the severing of the pipe A, bar or other like piece of work.

105 It is of course to be understood that the kerf or slot 10 can be disposed in true transverse position through the body 5 of the miter box or frame yet the said kerf or slot can be disposed at any desired angle according to the nature of the cut to be made in the bar or the like in the use of the miter box 110

for the severing of said pipe, bar or the like, either at an angle or straight across the same as the occasion may require.

The miter box in the construction thereof is especially adaptable in cutting pipes, iron or other like pieces of work and the same is applied thereto in the manner as shown in Figs. 1, 2 and 3 of the drawing, so that the hand of the operator of the saw can grip 10 the miter box through the loop recesses 7 and also the piece of work disposed within the box, the latter being in bridging relation to the work, thus it being seen that the work and the miter box will be firmly held against 15 displacement so that the hack saw when operated in the kerf or slot 10 will be guided for the severing of the work. If found expedient the miter box in the construction as hereinbefore set forth can clamp a piece 20 of work in any desirable manner other than the hand clamping thereof as is illustrated in Fig. 1 of the drawing.

It is of course to be understood that changes, variations and modifications may 25 be made in this invention, such as come properly within the scope of the appended claims, without departing from the spirit of the invention or sacrificing any of its advantages.

30 It is thought that the construction and manner of use of the miter box will be clearly understood and therefore a more extended explanation has been omitted.

What is claimed is:

1. A miter box of the character described, 35 comprising a substantially V-shaped frame adapted to be inverted for bridging a piece of work and having a kerf therein for guiding a hack saw operated for severing the piece of work, opposite portions of the 40 frame being cut away to permit the simultaneous gripping of said frame and the piece of work.

2. A miter box of the character described, 45 comprising a substantially V-shaped frame adapted to be inverted for bridging a piece of work and having a kerf therein for guiding a hack saw operated for severing the piece of work, the frame being provided with finger recesses in the sides thereof to 50 effect a hand grip on the frame and piece of work when the said frame is in inverted bridging relation to the work.

3. A miter box comprising a body, having 55 a V-shaped space for receiving a piece of work, said frame being formed with a kerf intersecting said V-shaped space transversely to the longitudinal extent thereof, said frame being further formed with recesses to accommodate the fingers and thumb 60 of the hand of a user for the gripping of said frame and a piece of work when disposed within the V-shaped space.

In testimony whereof I affix my signature hereto.

JOHN HOWARD THORNTON,
